UNITED STATES PATENT OFFICE.

AUGUST JOHNSON, OF LIVINGSTON MANOR, NEW YORK.

STEAM-BOILER.

1,241,985.

Specification of Letters Patent.

Patented Oct. 2, 1917.

Application filed January 22, 1917. Serial No. 143,636.

To all whom it may concern:

Be it known that I, AUGUST JOHNSON, a citizen of the United States, residing at Livingston Manor, in the county of Sullivan and State of New York, have invented certain new and useful Improvements in Steam-Boilers, of which the following is a specification, reference being had therein to the accompanying drawings.

10 This invention relates to improvements in steam boilers, and although applicable to locomotive boilers it is readily applied to any class of boilers for the generation of steam, the main object of the invention being 15 the provision of means whereby the boiling area is greatly increased and a greater steaming capacity is secured with the minimum amount of fuel.

A further object of this invention is the 20 provision of a novel arrangement of water carrying device adapted to be disposed and exposed within the fire box and to have communication with the water space of the boiler through a novel arrangement whereby 25 the proper circulation of steam is provided and at the same time should any burst occur within the pipes such pipes will be automatically closed due to the pressure and will, therefore, be isolated from the remainder 30 of the pipes without detrimentally affecting the steaming capacity of the boiler.

With the foregoing and other objects in view which will appear as the description proceeds, the present invention resides in 35 the combination and arrangement of parts hereinafter set forth and claimed, the scope of the invention being limited, however, only by what is claimed as many detail changes may be resorted to in the proper installation 40 of various boilers of the present apparatus.

In the accompanying drawings:

Figure 1 is a longitudinal sectional view through the fire box end of a locomotive boiler.

45 Fig. 2 is a section taken on line 2—2 of Fig. 1.

Fig. 3 is a cross section through the boiler taken on line 3—3 of Fig. 2.

Fig. 4 is an enlarged detail sectional view 50 of the end corner of the fire box showing the arrangement of one of the longitudinal and one of the transverse pipes.

Figs. 5 and 6 are detail views of the outside pipe connection and the automatic 55 means for closing a bursting pipe.

Fig. 7 is an enlarged detail view showing

the method of connecting or mounting the pipe ends.

Fig. 8 is an enlarged sectional view of the lower end of one of the exterior pipe connections showing the ball valve and its seat.

Referring to the drawings, the numeral 10 designates the fire box of a locomotive boiler 11 which is here shown as indicative of any form of steam generator upon which the present invention can be used.

The fire box is as usual surrounded by the shell 12 which provides with the outer wall 13 of the boiler, the water space 14, a water space 15 also being provided between the front walls 16 and 17 of the respective fire box and boiler. Thimbles or sleeves S are disposed within the sides between the walls 12 and 13 the ends being spun to maintain the same in place. Disposed longitudinally of and within the fire box are the two hollow water carrying members 18 each one of which is provided with the web portion 19 having recesses 20 at the upper edge thereof, the purpose of which will presently appear.

75 The forward reduced ends 21 of each conduit extends through the space 15 and its sleeve S and is connected as shown in Fig. 7 to an interiorly threaded nipple 22 carrying a disk or plate 23 attached upon the outside of the wall 17, the bolts 24 carried by the plate 23 being adapted to engage the plate 25 with a suitable gasket therebetween so as to secure the coupling 26 in position with its attaching plate 27 held by the bolts 28 to the plate 29 and for communication with the port 30.

85 Mounted in each one of the couplings 26 in the enlargement 31 thereof, is a ball valve 32 which is held above the sediment chamber 33 by means of the resilient spaced members 34, a clean-out plug 35 being disposed to permit of access to the coupling 26 and also the end of the pipe 21. The valve seat 36' is provided to receive the ball due to a 90 bursting of the pipe 21.

95 At the opposite end 36 of each member 18 is attached a similarly constructed coupling 26'. By these means it will be seen that water is permitted the proper circulation through the coupling 26 and the pipe 21 into the conduit 18 where steam is generated and permitted to flow through the pipe 36 and the coupling 26 into the steam dome of the boiler. Should any breakage 105 occur within the conduit 18 the outlet of steam within the fire box will cause the 110

steam to flow through the respective couplings 26 and 26' so that the ball valve will be forced to close the respective ends of the pipes 21 and 36 and thus isolate the coupling 18 from the rest of the generating system.

Also disposed within the fire box are the alternately disposed transverse pipes 37 and 38, the detail construction of each of which 10 is identical but whose respective short and long legs are alternated with opposite sides of the fire box.

In each instance the terminal end of the long leg 39 is in communication with the 15 lower end of the respective casings 26'' while the short legs 40 are in communication with the upper couplings 26^a, these couplings 26'' and 26^a being identical with the construction shown in Figs. 5 and 6 and 20 operating in a similar manner. The respective pipes 37 and 38 are so constructed so as to rest in alined recesses 20 of the supporting conduits 18 so that they are held in proper spaced relation and also without 25 throwing any particular strain upon the respective casing 26^a within the fire box.

It is apparent from the foregoing that this arrangement of steam generating tubes or pipes may be placed in the fire box of 30 locomotive or other boilers and that a greater steaming area within the fire box will be provided without increasing the combustion area, thus producing an exceedingly economical and efficient steam generator.

35 It is also apparent from this arrangement that the longitudinal and transverse conduits may be readily cleaned or blown out by the simple removal of the clean-out plugs and that by the bursting of any one of the 40 conduits the complete generator is not placed out of commission.

By mounting the pipes 18 and 21 in the sleeves S as shown, the same are readily removable without interfering with the water 45 space around the fire box, this often being necessary when desired to renew or repair such pipes or conduits.

What I claim as new is:

1. The combination with a steam generator having a fire box and a water space, 50 of an auxiliary generator including a plurality of supporting conduits mounted within the fire box and having the respective ends thereof projected through to the exterior of the boiler, a coupling member for each end of said conduits forming an exterior communicating means between the ends of the conduits and the water space of the boiler, a plurality of supported conduits disposed at right angles to the supporting conduits and having their ends disposed at different levels and projecting to the exterior of the boiler, and a coupling member for each end thereof disposed exteriorly of the boiler and providing a com-

municating means between each end of said supported conduits and the water space of the boiler.

2. The combination with a steam generator having a fire box and a water space, 70 of an auxiliary generator including a plurality of supporting conduits mounted within the fire box and having the respective ends thereof projected through to the exterior of the boiler, a coupling member for each end of said conduits forming an exterior communicating means between the ends of the conduits and the water space of the boiler, a plurality of supported conduits disposed at right angles to the supporting 75 conduits and having their ends disposed at different levels and projecting to the exterior of the boiler, a coupling member for each end thereof disposed exteriorly of the boiler and providing a communicating means between the ends of the supported conduits and the water space of the boiler, and a valve mounted in each coupling member for automatically closing the end of its respective conduit due to a burst in such conduit within the fire box. 90

3. The combination with a steam generator having a fire box and a surrounding water space, of an auxiliary generating apparatus including two longitudinally disposed supporting conduits mounted within the fire box and having the ends thereof projected through the walls of the fire box and boiler, two coupling members to each conduit attached to the outer wall of the boiler and in communication with the end of the conduit and the boiler, a plurality of transverse conduits mounted within the fire box and resting upon the supporting conduits, each of said transverse conduits being 95 provided with a lower terminal extending parallel to the side walls of the fire box and projecting through the water space to the exterior of the boiler, a coupling member attached to the wall of the boiler and 100 providing communicating means with the end of said conduit and the water space of the boiler, the upper end of each transverse conduit being projected through the side wall of the fire box to the exterior of the 105 boiler, and a coupling member attached to the outer end of said conduit and forming communicating means therewith and the steam dome of the boiler. 110

4. The combination with a steam generator having a fire box and a surrounding water space, of an auxiliary generating apparatus including two longitudinally disposed supporting conduits mounted within the fire box and having the ends thereof projected through the walls of the fire box and boiler, two coupling members to each conduit attached to the outer wall of the boiler and in communication with the end of the conduit and the boiler, a plurality of 115

transverse conduits mounted within the fire box and resting upon the supporting conduits, each of said transverse conduits being provided with a lower terminal extending 5 parallel to the side wall of the fire box and projecting through the water space to the exterior of the boiler, a coupling member attached to the wall of the boiler and providing communicating means with the end 10 of said conduit and the water space of the boiler, the upper end of each transverse con-

duit being projected through the side wall of the fire box to the exterior of the boiler, a coupling member attached to the outer end of said conduit and forming communicating means therewith and the steam dome of the boiler, and a valve mounted within each coupling and disposed to automatically close the end of its respective conduit due to a burst thereof in the fire box. 15

In testimony whereof I affix my signature.
AUGUST JOHNSON.
